[57] CLAIM

The ornamental design for a quick release buckle, as shown and described.

DESCRIPTION

FIG. 1 is a perspective view of a buckle in accordance with this invention in an engaged condition;

FIG. 2 is a top plan view of the buckle of FIG. 1;

FIG. 3 is a bottom plan view of the buckle of FIG. 1;

FIG. 4 is a male end elevational view thereof;

FIG. 5 is the female end elevational view thereof;

FIG. 6 is a left side elevation view of the buckle of FIG. 1 in an engaged condition;

FIG. 7 is a perspective view of the receiving or female part of the buckle of FIG. 1;

FIG. 8 is a perspective view of the engaging or male part of the buckle of FIG. 1;

FIG. 9 is a top plan view of the receiving or female part of the buckle of FIG. 7;

FIG. 10 is a side elevation of the receiving or female part of the invention as shown in FIGS. 7 and 9, the opposite side being than the mirror image thereof;

FIG. 11 is a top plan view of the engaging or a male part of the buckle of this invention as shown in FIG. 8;

FIG. 12 is a side elevation view of the engaging or male part of this invention as shown in FIGS. 8 and 11, the opposite side being the mirror image thereof;

FIG. 13 is a bottom plan view of the receiving or female part shown in FIGS. 7 and 9; and,

FIG. 14 is a bottom plan view of the engaging or male part of the buckle of this invention as shown in FIGS. 8 and 11. The portions of the drawings shown in dashed lines do not constitute part of the design.
